Des. 1097

John McMurry, of Fayette, Ky.

A assignor to

Geo. C. McMurry, of same place.

Letters Patent No. 1097, dated May 3, 1859.

The schedule referred to in these Letters Patent and making part of the same,

To all whom it may concern:

Be it known that I, John McMurry, of the County of Fayette and State of Kentucky, have invented, or produced a new and original design for Burial Bases, and I do hereby declare that the following is a full and exact description of same.

The accompanying drawings to which reference is here made, represent the different views of my design for a Burial Base.

Figure 1. Represents a side view of do do.

Do. 2 do an end do do do.

Do. 3. do A ground plan, do do.

Do. 4 do A top view of do do and showing the plates of glass in the roof of same.

What I claim and desire to secure by letters Patent, is,

The design for a Burial base of the form and style represented in the accompanying drawings.

Witnesses,

Inv. C. Hanks Jr.

Isaac Cook.

John McMurry.
